CIRCULAR-DECK CONCENTRATOR.

Application filed September 24, 1926. Serial No. 137,483.

This invention relates to circular concentrator tables and more particularly to a novel construction of the circular deck.

Circular concentrator decks have an important advantage over the usual straight concentrator decks, in that the circular deck affords a much longer travel of the material upon a deck surface within a small area than is afforded by the straight decks, but this advantage is offset by the disadvantage due to the fact that the movement imparted to the materials being treated is necessarily more energetic near the outer periphery of the deck than at points near the central axis of the deck.

In the present construction this objectional feature of circular decks is minimized by confining the materials delivered to the deck surface to a portion of the deck surface lying near the inner periphery of the deck, until after the materials have undergone a preliminary vibratory or settling treatment; and it is further minimized by the construction whereby the tailings are caused to flow over the riffles toward the outer periphery of the deck while the concentrates are directed against a concentrate wall lying between the riffles and the inner periphery of the deck.

In other words, the present construction is such that the tailings are caused to move outwardly toward the outer periphery of the deck where the greatest vibratory movement is imparted to the deck, while the concentrates are directed against a concentrate wall lying nearer the central axis of the deck, and as a result the concentrates are subject to a vibratory movement that is less energetic than that to which the tailings are subjected.

One important feature of the present invention therefore resides in a circular deck which is constructed to direct the tailings outwardly over the riffles so that they are carried a greater distance from the central axis of the deck than the concentrates.

The movement of the tailings outwardly away from the central axis of the deck may be promoted by imparting a downward slope to the deck in an outward direction, and another feature of the invention resides in a circular deck surface that slopes in a downward direction toward its outer periphery.

It is found that the values which remain in the tailings that reach the outer wall of the circular deck may be removed by subjecting the tailings to a panning action while

upon the deck surface. Another feature of the present invention therefore resides in a circular deck having a high wall extending part way around its outer periphery and which serves to confine the tailings so that they pile up against this wall and are subjected to a panning or settling action that causes the remaining concentrates to work down under the tailings into the channels formed by the riffles.

Still another feature of the invention resides in novel means for vibrating or rocking the circular deck.

Other features of the invention and novel combination of parts in addition to the above will be hereinafter described in connection with the accompanying drawings which illustrate good practical forms of the invention.

In the drawings:

Fig. 1 is a side elevation of a circular concentrator constructed in accordance with the present invention;

Fig. 2 is a top plan view of Fig. 1; 80

Fig. 3 is an enlarged perspective view of the concentrator deck;

Fig. 4 is a central sectional view through the deck of Fig. 3;

Fig. 5 on an enlarged scale is a sectional view taken on the line 5—5 of Fig. 2; 85

Fig. 6 is a perspective view of the cables and associated mechanism for rocking the deck; and

Fig. 7 is a sectional view through the cable actuating sheaves. 90

The circular deck forming the subject matter of the present invention may be supported for rotative or rocking movement in a horizontal plane by any suitable supporting structure, and the supporting frame shown has the longitudinally extending rails 10 secured to the uprights 11 at the opposite sides of the frame. These uprights are connected by the transversely extending beams 12, and near the longitudinal axis of the supporting frame are provided the longitudinally extending beams 13 which are held in spaced relation to each other by the central uprights 14 to which they are secured. The intermediate beams 13 serve to support bearing brackets to be described. The circular deck shown is provided with an annular casting or frame having a central hub 15 which is connected to the outer portion 16 of the frame by the spokes 17. In order to support the circular deck for rotative movement

the hub 15 of the annular casting is rigidly secured to the upper end of a vertically disposed shaft 18, and the upper portion of this shaft is rotatably mounted in a bearing bracket 19 which is rigidly secured to the upper beams 13 of the concentrator frame, while the lower end of this shaft is rotatably mounted in a bearing bracket 20 rigidly secured to the lower beams 13 of the supporting frame.

The deck surface 21 is preferably supported above and in spaced relation to the annular portion 16 of the rotating frame or casting, this being desirable to provide the air chamber 22 below the deck surface. The deck surface which may have the form of a wide annular disk or sheet is provided with the inner circular wall 23 and the outer circular wall 24, which extends upwardly from the supporting structure 16 to the deck surface to complete the formation of the air chamber 22 below the deck surface.

In accordance with the present invention the materials to be treated are delivered to the deck surface near its inner wall 23 and to this end the feed hopper 25 is provided having the sliding gate 26 for controlling the flow of materials from the hopper to the deck surface. It is desirable to confine the materials upon the deck surface near the feed hopper to that portion of the deck lying near its inner periphery until after these materials have been subjected to a preliminary stratifying operation under the influence of the vibratory movement imparted to the deck. In order to confine the materials to this portion of the deck the upstanding wall 27 is provided upon the deck surface and is sufficiently tall to prevent the materials upon the deck surface from passing outwardly over this wall until after they have traveled a substantial distance upon that portion of the deck lying near the inner annular wall 23, as will be apparent from Fig. 3. The portion of the inner wall 23 lying near the feed hopper 25 preferably extends upwardly a substantial distance above the deck surface as at 28, this being desirable to prevent the materials lying upon that portion of the deck surface adjacent the feed hopper from escaping inwardly over the inner edge of the deck. After the materials delivered to the deck surface by the feed hopper 25 have been subjected to the desired preliminary stratifying operation while they are retained between the spaced walls 27 and 28, they are allowed to spread out over a wider area of the deck surface, and to this end the curved upstanding wall 27 has the end portion 29 which extends outwardly towards the outer curved wall 24 of the circular deck.

Upon the deck surface 21 are provided the upstanding riffles 30 and these riffles as shown are disposed concentric with the cen-

tral axis of the circular deck and extend spirally over the deck surface through more than a complete circle.

In accordance with the present invention the concentrate wall 31 is disposed at the inner side of the circular deck so that it is surrounded by the riffles 30, and this concentrate wall is shown as extending in a spiral manner over the deck surface so that one end of the concentrate wall 31 lies in close proximity to the inner periphery of the deck, as clearly shown in Figs. 2 and 3. The concentrate wall 31 is provided with the portions 32 which form buffer blocks one of which is disposed adjacent an end of each of the riffles 30. The buffer portions 32 serve to give the concentrate wall the stepped construction shown, whereby each section 33 of the wall is disposed a greater distance from the inner periphery of the deck than the preceding sections 33. The riffles 30 preferably taper somewhat in the direction in which they extend so that they are relatively tall near the feed hopper 25, but are quite narrow at the discharge ends which terminate along the concentrate wall 31.

As above pointed out one of the advantages of a circular deck over the straight deck construction resides in the fact that a circular deck of relatively small area will afford a comparatively long path of travel of the materials over the deck surface due to the fact that the materials travel in more or less of a circular path in advancing over the deck surface. In order to increase the length of the path over which the materials travel upon the deck surface the present invention contemplates a construction whereby the riffles 30 lying near the outer periphery of the deck are arranged so that they extend around the inner riffles 30 in overlapping relation, as will be apparent from Figs. 2 and 3. As a result of this construction the materials delivered to the deck surface may travel over the deck surface in a spiral manner through a distance of more than one complete revolution. This is desirable as it will give the materials being treated a greater length of time to stratify and will effect a more complete separation of the tailings from the concentrates. In some cases it may be desirable to reduce the width of the channels between the riffles 30 near the discharge ends of the riffles. This is accomplished in the construction shown by bending the end portions of the riffles inwardly slightly towards the concentrate wall, as indicated by 30^a in Fig. 5. The reduction of the channels in this manner serves to crowd the tailings out of the channels to thereby promote their separation from the concentrates. The deck surface 21 may be provided with the apertures 34 to permit the air confined in the air chamber 22 to pass upwardly through the apertures and through

the materials being treated upon the deck surface. These apertures may be provided throughout the entire deck surface, or if desired they may be provided only adjacent to the feed hopper 25, as shown in Fig. 2, and air may be forced into the air chamber 22 by any suitable means (not shown).

The construction and operation of the present circular deck is such that the tailings are caused to flow outwardly over the

10 riffles 30 towards the outer edge of the deck while the concentrates are prevented by the riffles from traveling outwardly with the tailings. It is found that the tailings which have reached the outer portion of the deck surface may be subjected to a further treatment to remove the remaining values by subjecting these tailings to a panning action.

15 In order to accomplish this, in accordance with the present invention the circular deck is provided at its outer periphery with a relatively high tailing retaining wall 35, this wall being so constructed that it will confine the tailings upon the deck surface

20 adjacent the outer periphery of the deck until they have traveled a substantial distance along this retaining wall 35. By retaining a relatively thick layer or bank of the materials upon the deck surface adjacent

25 the wall 35, these materials are subjected to a panning action due to the vibratory movement imparted to the deck, with the result that the values suspended in the tailings are caused to work downwardly into the chan-

30 nels between the riffles 30 and they will travel within these channels around the deck surface until they finally escape into the receptacle provided to receive such concentrates.

35 After the tailings have traveled a desired distance along the retaining wall 35 they are permitted to escape over a reduced portion 36 of this wall into a tailing receiving trough 37 that may extend around the outer periphery of the deck any desired distance. The tailings which fall into the trough 37 are removed therefrom through a discharge opening 38 provided at one end of this trough. The middlings or materials which

40 escape over the outer periphery of the deck surface at a point beyond the curved trough 37 may fall into a second trough 39 which is secured to the outer periphery of the concentrator deck and the materials which accu-

45 cumulate in this trough 39 may escape through the discharge spout 40. The concentrates which are directed against the concentrate wall 31 by the riffles 30 will pile up against the different buffer blocks 32 and

50 flow outwardly over the adjacent riffles for further treatment, and after these concentrates have traveled along the concentrate wall for the desired distance they may be drawn off through a gate 41 into the concentrate trough 42 along which they may

travel to a discharge spout 43 extending downwardly through the floor of the deck. The concentrates which accumulate along the concentrate wall at a point beyond the discharge gate 41 are received in the concentrate hopper 44, and such concentrates as remain in the channels formed by those riffles lying adjacent the outer periphery of the deck may likewise pass into the concentrate hopper 44.

55 The deck surface 21 may lie in a horizontal plane, as shown in the embodiment of the invention disclosed in Fig. 1, or the deck surface may slope downwardly slightly in an outward direction, as shown in Fig. 4. 60 The rocking or vibratory movement imparted to the deck will tend to throw the tailings outwardly in a tangential direction towards the outer periphery of the deck, but the travel of the materials outwardly towards the outer edge of the deck may be assisted by sloping the deck downwardly towards its outer periphery, as shown in Fig. 4.

65 As a result of the deck construction shown and described, the concentrates accumulate along the concentrate wall disposed near the inner periphery of the deck, whereas the tailings are caused to flow outwardly over the riffles towards the outer edge of the deck. 70 This causes the tailings to be subjected to a stronger vibratory movement than the concentrates, since materials lying near the outer periphery of a rotating deck are necessarily subjected to a stronger vibratory force 75 than the materials lying nearer the central axis of the deck. It will therefore be seen that the strongest movement in the present construction is utilized to advance the tailings or lighter materials over the deck surface, which is desirable.

80 The means employed for imparting a back and forth or rocking movement to the circular deck may be variously constructed, but the construction of the operating means should be such that it will impart a pronounced progressive movement to the materials upon the deck surface, this being essential because in the construction shown the movement is relied upon almost entirely to work the tailings outwardly towards the outer edge of the deck, for, as above pointed out, the slope imparted to the deck surface is relatively slight. One good practical means for imparting a progressive vibratory movement to the deck consists of an operating cable 45, an intermediate portion of which is looped about an annular drum 46 which extends downwardly from the annular casting 16 of the circular deck, and the portion of the cable which is looped about the drum 46 is preferably secured thereto by a clamp 47 in order to prevent the cable from slipping around the drum. One end portion of the cable 45 is looped about and

the end of this cable is rigidly secured to a grooved sheave 48 disposed near the left-hand end of the concentrator frame viewing Fig. 1, and this sheave is rotatably supported by a shaft 49 mounted in bearing blocks 50 secured to the supporting frame. The opposite end portion of the cable 45 extends around and is secured to a similar grooved sheave 51 disposed at the right-hand side of the supporting frame and this sheave is mounted upon the shaft 52 having the bearing brackets 53.

In order to impart the desired progressive movement to the circular deck it is necessary to pull the opposite ends of the cable 45 with a variable speed movement. This is accomplished in accordance with the present invention by providing the cables 54 and 55, each of which has one end anchored to the transversely extending beam 56 of the supporting structure, while the other end of each of these cables passes partly around the grooved sheave 48 and is rigidly secured to this sheave by the clamp 57. An intermediate portion of the cable 54 is looped about a grooved sheave 58 which is mounted upon an eccentric 59 that is rigidly secured to and is rotated by the power operated shaft 60, the eccentric 59 being constructed to rotate within the sheave 58. The other cable 55 is looped about a grooved sheave 61 which is mounted upon a second eccentric 62 which is driven by the shaft 60 to rotate within the sheave 61. Rocking movement is imparted to the sheave 51 by the cables 63 and 64 each of which has one end yieldingly attached to the beam 56 by a spring 56^a and the other end of each of these cables extends part way around the grooved sheave 51 and is secured thereto by the clamp 65. An intermediate portion of the cable 63 is looped about a second groove formed in the sheave 58, and the cable 64 is looped about a second groove in the sheave 61.

The eccentrics 59 and 62 are disposed at an angle to each other, say an angle of 180°, and the construction is such that as the eccentric 59 rotates through a complete revolution it will move its sheave 58 through an orbital path to thereby alternately slack off and tension the cables 54 and 63 engaging this sheave. As the eccentric 62 rotates through a complete revolution it will move its sheave 61 through an orbital path to tension and slack off the cables 55 and 64. The arrangement is such that the pair of cables actuated by the eccentric 59 will serve to rock the deck back and forth and the same is true of the pair of cables engaging the eccentric 62, but each eccentric will serve to modify the action of the other eccentric upon the deck to thereby impart the desired progressive movement to the circular deck. In other words, rotation of the eccentric 59 serves to let off the cable 54 to effect rotation of the

deck in one direction with an increasing speed, and the slackening off of this cable at an increasing speed continues during the rotation of the eccentric through an angle of say 90°; whereupon rotation of the deck 70 under this let-off movement is suddenly reversed by the cable 55 which receives a quick take-up pull from its eccentric 62. Corresponding movements are imparted to the cables 63 and 64 by the eccentrics 59 and 62 75 and as a result the deck is pulled back and forth with a positive accelerated movement in one direction and a negative accelerated movement in the opposite direction. The movement imparted to the deck preferably 80 serves to rock the same through only a small angle.

The construction and operation of the cable operating mechanism shown in Fig. 6 and above described will be more clearly 85 understood upon reference to the A. H. Stebbins Patent No. 1,567,550, granted December 29, 1925, wherein this type of movement is employed to impart a progressive vibratory movement to a straight type of deck, 90 and in the present construction such changes have been made in the operating mechanism disclosed in the patent just mentioned as were necessary to employ this operating means in connection with a circular deck. 95

What is claimed is:—

1. A circular concentrator deck, comprising in combination, a deck frame, an annular deck surface upon said frame and having a tailing discharge near its outer periphery, a stepped concentrate wall positioned to extend spirally over the deck surface and having one portion that lies close to the inner periphery of the deck surface while the rest of the wall gradually recedes from such periphery, a feed hopper for delivering the materials to the deck surface adjacent its inner periphery, riffles extending over the deck surface and arranged to direct the concentrates against the stepped concentrate wall for retreatment, and means for vibrating the deck to effect movement of the tailings outwardly over the riffles toward said outer periphery. 110

2. A circular concentrator deck, comprising in combination, a deck frame, an annular deck surface supported by the frame so that it slopes slightly in a downward direction toward its outer periphery, riffles extending over the deck surface, a stepped concentrate wall positioned between the riffles and the inner edge of the deck and arranged to extend spirally over the deck surface in a direction to gradually direct the concentrates away from the inner edge of the deck, and means for vibrating the deck to work the stepped concentrates along the riffles against the concentrate wall for retreatment and to cause the tailings to flow over the riffles toward the outer edge of the deck. 125 130

3. A circular concentrator deck, comprising in combination, a deck frame, an annular deck surface supported by the frame, riffles extending over the deck surface and arranged in overlapping concentric coils that extend through more than a complete circle over the deck surface, a concentrate wall positioned between the riffles and the inner edge of the deck, and means for vibrating the deck to work the concentrates along the riffles against the concentrate wall and to cause the tailings to flow over the riffles toward the outer edge of the deck.

4. A circular concentrator deck, comprising in combination, a deck frame, an annular deck surface supported by the frame, a concentrate wall positioned to extend spirally over the deck surface and having one portion of its wall lying close to the inner periphery of the deck surface while the rest of the wall is disposed at a progressively increasing distance from said periphery, riffles positioned between the concentrate wall and outer periphery of the deck surface and adapted to direct concentrates against said wall for retreatment, and means for vibrating the deck to cause the concentrates to travel along the riffles and the tailings to flow over the riffles toward the outer periphery of the deck surface.

5. A circular concentrator deck, comprising in combination, a deck frame, an annular deck surface supported by the frame, riffles extending over the deck surface, a concentrate wall positioned between the riffles and the inner edge of the deck, means for vibrating the deck to work the concentrates along the riffles against the concentrate wall and to cause the tailings to flow over the riffles toward the outer periphery of the deck surface, a tailing receiving trough extending around the outer portion of the deck surface, and means for removing the tailings from the trough at different points along its length to separate the tailings into different grades.

6. A circular concentrator deck, comprising in combination, a deck frame, an annular deck surface supported by the frame and provided with air apertures, a concentrate wall positioned between the riffles and the inner edge of the deck, means for vibrating the deck to work the concentrates along the riffles against the concentrate wall and to cause the tailings to flow over the riffles toward the outer periphery of the deck surface, and means for forcing air upwardly through the deck surface to promote separation of the materials.

7. A circular concentrator deck, comprising in combination, a deck frame, an annular deck surface supported by the frame, means for delivering the materials to the deck surface at a point near its inner periphery, means for retaining the materials upon the

portion of the deck lying near its inner periphery until after they have undergone a preliminary stratifying operation, riffles extending over the deck surface, a concentrate wall disposed between the riffles and the inner edge of the deck, and means for vibrating the deck to work the concentrates along the riffles against the concentrate wall and to cause the tailings to flow over the riffles toward the outer edge of the deck.

8. A circular concentrator deck, comprising in combination, a deck frame, an annular deck surface supported by the frame, means for delivering the materials to the deck surface at a point near its inner periphery, a raised wall that extends upwardly from the deck surface a greater height than the riffles and positioned in spaced relation to the inner periphery of the deck surface to retain the materials upon the portion of the deck lying near its inner periphery until after they have undergone a preliminary stratifying operation, riffles extending over the deck surface, and means for vibrating the deck to work the concentrates along the riffles and to cause the tailings to flow over the riffles toward the outer periphery of the deck.

9. A circular concentrator deck, comprising in combination, a deck frame, an annular deck surface supported by the frame, riffles extending over the deck surface and arranged concentric with the central axis of the deck, a concentrate wall disposed near the inner periphery of the deck, and means for vibrating the deck to advance the concentrates along the riffles against the concentrate wall for retreatment and to work the tailings outwardly over the riffles.

10. A circular concentrator deck, comprising in combination, a deck frame, an annular deck surface supported by the frame and having a tailing discharge portion extending along the outer edge of the deck surface and a concentrate wall positioned between the inner edge of the deck and said outer discharge portion and arranged so that it gradually approaches the outer periphery of the deck in the direction in which the materials are advanced over the deck surface, means for delivering the materials to be treated to the deck surface, riffles extending over the deck surface to direct the concentrates against the concentrate wall for retreatment, and means for vibrating the deck to work the tailings over the riffles toward the outer edge of the deck.

11. A circular concentrator deck, comprising in combination, a deck frame, an annular deck surface supported by the frame, riffles extending over the deck surface and arranged in overlapping coils that extend through more than a complete circle and overlap in the same plane of the deck surface, a concentrate wall positioned between

the riffles and the inner edge of the deck, and means for vibrating the deck to work the concentrates along the riffles against the concentrate wall and to cause the tailings to flow over the riffles toward the outer edge of the deck.

12. A circular concentrator deck, comprising in combination, a deck frame, an annular deck surface supported by the frame, a concentrate wall having one end disposed near the inner periphery of the deck surface and arranged to extend spirally over the deck surface through more than a complete circle so that portions of the concentrate wall overlap in the same plane of the deck surface, means for delivering the materials to be treated to the deck surface, riffles for directing the concentrates against the spirally dis-

posed concentrate wall, and means for vibrating the deck to work the materials over its surface.

13. A circular concentrator deck, comprising in combination, a deck frame, an annular deck surface supported by the frame, riffles extending over the deck and arranged so that the riffles at the discharge end of the deck surround and overlap the riffles at the feed end of the deck, a concentrate wall lying between the riffles and the inner edge of the deck, and means for vibrating the deck to work the concentrates along the riffles against the concentrate wall.

In testimony whereof, I have signed my name to this specification.

ALBERT H. STEBBINS.
